[57] CLAIM

The ornamental design for a putter head, as shown and described.

DESCRIPTION

FIG. 1 is a top plan view of my putter head design; FIG. 2 is a perspective top view of my putter head design;

FIG. 3 is a perspective bottom view of my putter head design;

FIG. 4 is a bottom view of my putter head design;

FIG. 5 is a front elevational view of my putter head design;

FIG. 6 is a back elevational view of my putter head design; and,

FIG. 7 is a side elevational view of my putter head design.

The broken lines showing a putter shaft in FIGS. 1 and 2 are for illustrative purposes only in showing the relationship between the putter head of my design and a putter shaft, and forms no part of the claimed design.
